(57) **CLAIM**

The ornamental design for a pocket knife, as shown and described.

DESCRIPTION

FIG. 1 is a left perspective view of a pocket knife embodying the new design with the blade deployed;

FIG. 2 is a right side elevation view of the pocket knife with the blade deployed;

FIG. 3 is a left side elevation view of the pocket knife with the blade deployed;

FIG. 4 is a top plan view of the pocket knife with the blade deployed;

FIG. 5 is a bottom plan view of the pocket knife with the blade deployed;

FIG. 6 is a front side elevation view of the pocket knife with the blade deployed;

FIG. 7 is a rear side elevation view of the pocket knife with the blade deployed;

FIG. 8 is a right side elevation view of the pocket knife with the blade retracted; and,

FIG. 9 is a left side elevation view of the pocket knife with the blade retracted.

The broken lines depict portions of the pocket knife in which the design is embodied that are not considered part of the claimed design.

1 Claim, 5 Drawing Sheets
